Clarence O. Brown

Attorney

UNITED STATES PATENT OFFICE.

HENRY W. JOHNSON, OF DENMARK, SOUTH CAROLINA.

CIGAR AND CIGARETTE HOLDER.

Application filed January 7, 1925. Serial No. 1,068.

To all whom it may concern:

Be it known that I, HENRY W. JOHNSON, a citizen of the United States, residing at Denmark, in the county of Bamberg and 5 State of South Carolina, have invented certain new and useful Improvements in a Cigar and Cigarette Holder, of which the following is a specification.

This invention relates to improvements in 10 cigar and cigarette holders, and has for its primary object to provide a simple and efficient means whereby the person using the device may enjoy the full flavor and benefit of the cigar or cigarette without receiving 15 any of its harmful effects.

A further object of the invention is to 20 provide a cigar and cigarette holder of the above mentioned character, wherein means is arranged with the stem of the device in the path of the smoke for removing therefrom the nicotine and other deleterious matter therein.

A further object of the invention is to 25 provide a device of the above mentioned character, wherein the stem is formed of transparent material so that the absorbent packing disposed within the stem for preventing the nicotine and other deleterious matter from entering the mouth piece and 30 the mouth of the user, will at all times be visible thus enabling the user of the device to readily ascertain when it becomes necessary to replace the absorbent packing.

A further object of the invention is to 35 provide a device of the above mentioned character, wherein the several parts constituting the same may be readily and easily assembled or disassembled, the device being further simple in construction, inexpensive, 40 strong and durable and furthermore adapted for the purposes for which it is designated.

Other objects and advantages of this invention will become apparent from the 45 course of the following description.

In the accompanying drawing forming a part of this specification and in which like numerals designate like parts throughout the same:

50 Figure 1 is a side elevation of one form of the device.

Figure 2 is a longitudinal sectional view therethrough.

55 Figures 3 to 6 inclusive are longitudinal sectional views of modified forms.

Referring to the drawing, and more particularly to Figures 1 and 2, the device which it is of course understood may be used for holding either cigars or cigarettes, is constructed in three sections, 1, 2 and 3 60 respectively. The section 1 designates the stem, the mouth piece and socket member being designated by the sections 2 and 3 respectively. The stem 1 is formed of any suitable transparent material and is tubular 65 in cross section. The stem may be constructed of glass, or bakelite, and it is to be understood that I do not wish to limit myself to the particular kind of material to be used. An absorbent pad or packing of cotton is adapted to be disposed within the tubular stem 1 and is indicated at 4 with reference more particularly to Figure 2.

The mouth piece 2 is provided at one end with the usual bit 5 and at its opposite end 75 with an integral nipple 6. A longitudinally extending smoke passage or bore 7 is formed in the mouth piece and has communication with the stem 1. The socket member 3 is provided with the usual socket 8 for the reception of the cigar or cigarette, it being understood that the sockets in the holder are made of any suitable size for use with either cigars or cigarettes. The socket member is also provided with an integral 80 nipple 10 at its inner end and the same is provided with a central smoke passage or bore 11, whereby communication between the socket and the stem 1 is afforded. A metal ring such as is shown at 12 is detachably associated with the socket member 3, a portion of the ring being disposed within the socket and having the outer portion thereof engaging the outer edge of the socket member. 85

The nipples 6 and 10 are disposed within the respective ends of the stem 1 and suitable packing sleeves 13 of cork or other similar material produces a tight friction fit between the interior wall of the stem and 100 the nipple.

In Figure 3 of the drawing, a modification is shown wherein the stem 1 and the mouth piece 2 are constructed integrally, the tubular stem being provided with the chamber 14 for receiving the absorbent packing material and the mouth piece 2 being provided with the longitudinally extending smoke passage 15 which communicates with the chamber 14. In this instance, the outer 105 110

end of the stem is internally threaded to receive the threaded nipple 16 formed on the socket member 3.

In Figure 4, the position of the part is 5 reverse from that shown in Figure 3 in that the socket member 3 and the stem 1 are formed integrally, with a smoke bore 17 communicating the socket member 3 with the chamber 18 provided in the stem 1 for 10 receiving the absorbent packing material. In this form of the invention, the inner end of the stem is internally threaded to receive the threaded nipple 19 of the mouth piece 2.

Figure 5 is a view similar to Figure 2, 15 and in this form of the invention, the nipples are tapered for frictional engagement with the tapered inner wall of the stem at the respective ends thereof.

In Figure 6 of the drawing, a still further 20 modification is shown wherein the entire device is constructed of a single piece of material, no intervening part or section being disposed between the stem and the holder or socket member, the mouth piece 2 25 being further of considerable length and having the smoke passage or bore which extends longitudinally therethrough communicating with the stem. The absorbent packing material is disposed within the stem as 30 clearly illustrated in the drawing. If desired, an ornamental sleeve or band of metal such as is shown at 20 may be detachably associated with the socket member.

In any of the forms shown in the drawing, 35 the absorbent pad may be easily inserted or removed from the stem, in the forms shown in Figures 1, 2 and 5, either the mouth piece or socket member may be removed whereby access to the interior of the stem may be had. In Figure 3, the 40 socket member is removed while in Figure 4 the mouth piece is removed for inserting or removing the absorbent packing from the stem. In Figure 6, the packing is inserted 45 within the stem or removed therefrom through the socket member 3.

By placing the packing 4 within the stem 1, the smoke will be purified before the same reaches the mouth of the user of the 50 device, the packing 4 tending to remove the nicotine and other deleterious matter from the smoke before the same enters the smoke passage in the mouth piece. By constructing the stem of a transparent material, the 55 user of the device may at all times see the

packing within the stem and thereby ascertain when it becomes necessary to change the discolored absorbing packing. If the stem was not constructed of a transparent material, the user of the device would very 60 frequently draw a quantity of nicotine saturated saliva into his mouth from the absorbent packing without any previous warning that the absorbing packing has become over-saturated.

It is also to be understood that the mouth piece and socket member may be constructed of any suitable material. The interior of the stem and socket member are circular while the outer sides thereof may be of any 70 desirable shape such as hexagonal, flat, square, etc., in cross section. Also the connections between the stem and the socket member and mouth piece respectively may be packed, threaded or frictionally engaged.

The simplicity in which my improved cigar and cigarette holder is constructed enables the parts to be readily assembled or disassembled and will at all times be positive and efficient in carrying out the purposes for 80 which the same has been designated.

While I have shown the preferred embodiment of my invention, it is to be understood that various changes in the size, shape and arrangement of parts may be resorted 85 to without departing from the spirit of the invention and the scope of the appended claim.

Having thus described the invention, what I claim is:—

An article of the class described comprising a tubular transparent stem, a mouth piece, and a socket member, each provided with a smoke bore, and a longitudinally extending nipple, said nipples adapted to be 90 disposed within the respective ends of the transparent stem, and having their ends spaced from each other, a compressible packing sleeve surrounding said nipples and engaging the inner wall of the stem at the 95 respective ends thereof for frictionally securing the mouth piece and the socket member on the stem, and an absorbent packing within the stem, the same being adapted to fill the empty portion of the stem and engaging the inner opposed ends of said nipples.

In testimony whereof I affix my signature.

HENRY W. JOHNSON.
